DRAWING MECHANISM FOR TEXTILE SLIVERS

Ramon Balmes Solanas, Pinedes de Llobregat,
SpainApplication June 15, 1938, Serial No. 213,900
In Spain June 30, 1937

6 Claims. (Cl. 19—130)

My invention refers to drawing mechanisms for textile slivers provided with various pairs of rollers, used in spinning or preparatory machines for the spinning of cotton or other textile fibres 5 and will be described in the present specification as applied to a drawing mechanism of four pairs of rollers, composed of a first pair of feeding rollers or entrance rollers for the sliver, a second pair of intermediate rollers, which produce a draft 10 in combination with the feeding rollers, a third pair of retaining or slippage rollers, light and of small diameter and lastly a pair of final drawing rollers or delivery rollers for the thread, which are those that produce the final draft of the 15 sliver held by the intermediate rollers, the fibres slipping between the retaining or slippage rollers. In such drawing mechanisms, in the cases in which the first drawing is very strong, as happens in certain special mechanisms in which the first 20 pair of rollers or feeding rollers is constituted by a fluted roller and a roller covered with points or pins (porcupine roller), it happens that the fibres of the sliver in the length comprised between the two central pairs of rollers, remain very loose 25 from one another and distributed in a great width which is greater than the thickness of the sliver on entering in the drawing mechanism. This has the disadvantage that the fibres drawn by the final drawing rollers or delivery rollers bring 30 with them at intervals other fibres of the sliver, producing irregularities in the thickness of the thread and at the same time owing to the fibres remaining so loose and occupying too great a width they have a tendency to wind on the rollers 35 and on the thread or sliver leaving the final drawing rollers the fibres are not completely caught up by the twist but certain parts remain loose giving the thread a hairy appearance that it is difficult to correct.

40 The present invention avoids these troubles ensuring a proper guidance of the sliver and reducing at the same time the width in order to bring the fibres together.

45 The invention consists in arranging between the two central pairs of rollers, a roller that conducts or accompanies the sliver from one pair of rollers to the other, combined with one or more condensers or reducers of the width of the sliver, which oblige the fibres to approach together. This roller conductor of the sliver is arranged simply resting on the lower rollers of the two central pairs of rollers and is combined with a framework which carries on the lower part a small bar on which there can slide from one 50 side to the other a reducer of the width of the

sliver, so that this is obliged to pass below the conducting roller and to enter into the throat of the reducer. There may be combined also a second sliver reducer situated between the slippage rollers and the final delivery rollers and supported by some arms that proceed from the same framework that surrounds the conducting roller.

5 In the attached drawings there is shown the necessary part of a drawing mechanism of four pairs of rollers embodying the invention.

Figure 1 is a top view of the drawing mechanism with the top rollers of all the pairs of rollers removed.

Figure 2 is a cross section of the drawing mechanism according to the line II—II of Figure 1.

Figure 3 is a similar section according to the line III—III of Figure 1.

Figure 4 is a perspective view on a larger scale of the conducting roller of the sliver with the framework that holds the lower reducer and

Figure 5 is a similar view of a modification in which the framework in addition to holding the lower reducer carries a second reducer which remains interposed between the slippage rollers and the final drawing rollers.

25 As is shown in the drawings, the drawing mechanism includes in the usual way a pair of feeding rollers 1—2, a pair of intermediate rollers 3—4, a pair of retaining or slippage rollers 7—8 of 30 small diameter and a pair of final drawing or delivery rollers 5—6.

35 Rollers 2, 4, and 6 are conveniently loaded by means of a double saddle formed by two pieces 9, 10 pivotally connected at the point 11 and 35 which by means of the stay 12 receive in the usual way the action of a weight not shown in the drawings. This saddle 9, 10 forms at the same time a rest for the clearers 13.

40 In order to accompany the sliver in the part that goes from the tangency line of the two intermediate rollers 3—4 to the tangency line of the slippage rollers 7—8, there is arranged in accordance with this invention a roller 14 resting freely on the two rollers 3 and 7. This roller 45 14 has not any support to hold it but simply rests on the rollers 3 and 7 and is prevented from moving axially, on the one hand by the pressure saddle 9 and on the other by the support 15 of the top rollers of the drawing mechanism.

50 By the action of this conducting roller 14 the sliver, instead of leaving the roller 3 in the same tangency line of this roller with the top roller 4 is applied on the surface of the roller 3 until it arrives at the tangency line of the rollers 3 55

and 14 and then passes below the roller 14 until it arrives at the tangency line of the roller 14 with the slippage roller 7 and from this point remains applied on the surface of the roller 7 until its tangency line with the top roller 8.

5 This on the one hand reduces greatly the length of sliver that remains without support on the lower part and in addition owing to the large contact surface between the sliver and the rollers 10 3-7 increases the adherence of the fibres with these rollers and reduces considerably the possibility of the fibres coming off the sliver or becoming disarranged.

With this roller 14 there is combined a 15 denser or reducer 18 of the width of the sliver, situated underneath of the roller 14. This reducer 18 is held by a small framework 19 resting on the gudgeons 20 of the roller 14 and which presents on the lower part a small bar 21 on 20 which is threaded the reducer 18 in such a way that it can slide laterally following the reciprocating movement of the sliver. Preferably the framework 19 should form a prolongation or handle 22 which serves to be able to lift easily the 25 roller 14 with the reducer 18. The sliver on being caught by the pair of rollers 7, 8 is obliged to adapt itself against the lower surface of the roller 14 and against the reducer 18 penetrating into the throat made in the lower part of this 30 reducer, thus reducing the width of the sliver by the converging form of this throat.

It is advisable to arrange a second reducer 23 of the width of the sliver, situated between the slippage rollers 1-8 and the delivery rollers 5-6. 35 This reducer may be supported in different ways but preferably it is arranged supported by the same framework that supports the lower reducer 18 as is shown in the drawings and in greater detail in Fig. 5. For this, there is arranged on 40 the framework 19 a supplementary framework formed by the two arms 24 joined together by a crosspiece 25 and by a front bar 26 on which there is threaded the reducer 23 in such a way that it may slide following the reciprocating 45 movement of the sliver. The arms 24 have slots 27 that fit in the projections 28 of the framework 19 in order that the reducer 23 may situate itself in the proper position, adapting itself to the different separations or distances between 50 the pairs of rollers of the drawing mechanism.

Below the arms 24 the framework carries projecting fingers 29 for limiting the downward movement of these arms when there is withdrawn from the machine the roller 14 with the framework and the reducers and in this way to obtain that on putting it back again, the reducer 23 shall take the proper working position.

Both the reducer 18 as well as the reducer 23 have the throat made in the lower part, which 60 not only is more convenient owing to the manner in which the sliver passes in this apparatus, but in addition has the important advantage that the roller 14 with the framework and the two reducers may be withdrawn without in any way 65 having to dismount the drawing mechanism. Preferably there is made in the reducer 23 a shoulder or inclined plane 33 on one of its sides, such as is shown in Fig. 5 in order to facilitate 70 the threading of the sliver on placing into position the roller 14 with the reducers. Thanks to this inclined plane, the sliver itself in its cross reciprocating movement makes the reducer 23 swing slightly until it fits in the throat of the same, after which the sliver draws in the normal way 75 the reducer 23 in its movement.

By the effect of the arrangement described, the reducer 23 can engage itself easily in the angle formed by the two rollers 5-6 and the slots 27 allow it to always adopt this correct position, even when the separation between the rollers 5-6 and 3-4 varies.

I claim:

1. In a drawing mechanism according to claim 3, a framework surrounding the conducting roller for the sliver and carrying underneath said roller 10 the reducer of the width of the sliver, two arms projecting from the sides of said framework towards the delivery rollers, said arms being connected together and carrying a second reducer of the width of the sliver in such a way that it 15 remains lodged in the angle formed by the two delivery rollers; the conducting roller, the framework and the two reducers forming thus a unit which can be easily removed and replaced in the 20 mechanism.

2. In a drawing mechanism according to claim 3, a framework surrounding the conducting roller for the sliver and carrying underneath said roller a reducer of the width of the sliver, said framework comprising two lateral plates, means for 25 connecting said plates, and a lower bar on which the reducer may slide freely; two arms in said framework which carry a second reducer of the width of the sliver near the delivery rollers, said arms having slots for sliding over fingers projecting from said lateral plates in such a way that the reducer may engage itself automatically the 30 angle formed by the two delivery rollers, and projecting fingers in said lateral plates underneath said arms to limit the movement of said arms when said conducting roller, with said framework and said reducers, are removed from the 35 mechanism.

3. A drawing mechanism for textile slivers comprising a series of pairs of rollers, a conducting 40 roller for the sliver located between two consecutive pairs of rollers, said conducting roller resting freely on the lower rollers of said consecutive pairs and a reducer of the width of the sliver located below said conducting roller and closely 45 adjacent the same to accompany the sliver in the remaining space between said consecutive pairs and simultaneously reducing the width of the sliver.

4. A drawing mechanism for textile slivers comprising a series of pairs of rollers, a conducting roller for the sliver located between two consecutive pairs of rollers, said conducting roller resting freely on the lower rollers of said consecutive pairs, a reducer of the width of the sliver located 55 below said conducting roller and closely adjacent the same to accompany the sliver in the remaining space between said consecutive pairs and simultaneously reducing the width of the sliver, gudgeons upon said conducting roller, a framework mounted on said gudgeons surrounding said conducting roller and a bar upon the lower portion of said framework on which said reducer is mounted freely slidable.

5. A drawing mechanism for textile slivers comprising a series of pairs of rollers, a conducting roller for the sliver located between two consecutive pairs of rollers, said conducting roller resting freely on the lower rollers of said consecutive pairs, a reducer of the width of the sliver located 70 below said conducting roller and closely adjacent the same to accompany the sliver in the remaining space between said consecutive pairs and simultaneously reducing the width of the sliver, a framework surrounding said conducting roller 75

In which said reducer is mounted, said framework comprising two lateral plates, means for connecting said plates, a lateral bar on said framework on which said reducer is freely slideable, two arms 5 upon said framework, a second reducer of the width of the sliver supported from said last mentioned arms adjacent the delivery rollers, said arms having slots, fingers projecting from said lateral plates into said slots so that said second 10 reducer may be automatically engaged in the angle formed by the two delivery rollers, projecting fingers in said lateral plates located underneath said arms for limiting the movement of said arms when said conducting roller together 15 with said framework and said reducers are removed from the mechanism and said reducers being open at the lower portion so as to permit the removal and replacement of the conducting roller with the framework and reducers without 20 breaking the sliver.

6. A drawing mechanism for textile slivers comprising a series of pairs of rollers, a conducting roller for the sliver located between two consecutive pairs of rollers, said conducting roller resting 25 freely on the lower rollers of said consecutive pairs, a reducer of the width of the sliver located below said conducting roller and closely adjacent the same to accompany the sliver in the remain-

ing space between said consecutive pairs and simultaneously reducing the width of the sliver, a framework surrounding said conducting roller in which said reducer is mounted, said framework comprising two lateral plates, means for connecting said plates, a lateral bar on said framework on which said reducer is freely slideable, two arms 5 upon said framework, a second reducer of the width of the sliver supported from said last mentioned arms adjacent the delivery rollers, said 10 arms having slots, fingers projecting from said lateral plates into said slots so that said second reducer may be automatically engaged in the angle formed by the two delivery rollers, projecting fingers in said lateral plates located underneath said arms for limiting the movement of 15 said arms when said conducting roller together with said framework and said reducers are removed from the mechanism and one of said reducers having an inclined plane at its lower side 20 leading to the throat of said reducer in such a way that on replacing the conducting roller with the reducers in the mechanism the sliver in its reciprocating movement will act on said inclined plane to lift the reducer and permit the sliver to 25 automatically enter into the throat of such reducer.
